(57) **CLAIM**

The ornamental design for an insert for connector, as shown and described.

DESCRIPTION

FIG. 1 is a top plan view of a first embodiment of an insert for connector, showing my new design;

FIG. 2 is a top, right, rear perspective view thereof;

FIG. 3 is a front elevational view thereof; the left and right side elevational views are identical thereto;

FIG. 4 is a rear elevational view thereof;

FIG. 5 is a bottom plan view thereof;

FIG. 6 is a top, left, rear perspective view thereof;

FIG. 7 is a top plan view of a second embodiment of an insert for connector, showing my new design;

FIG. 8 is a top, right, rear perspective view thereof;

FIG. 9 is a front elevational view thereof; the left and right side elevational views are identical thereto;

FIG. 10 is a rear elevational view thereof;

FIG. 11 is a bottom plan view thereof; and,

FIG. 12 is a top, left, rear perspective view thereof.

Throughout the drawings, a dot-dash patterned line is used to depict the boundaries of the claimed design, it being understood that the claimed design extends to the boundaries but that the boundary lines form no part of the claimed design. Additionally, throughout the drawings, dashed lines of evenly-sized line segments are used to depict portions of the insert for connector that form no part of the claimed design.

1 Claim, 10 Drawing Sheets
